UNITED STATES PATENT OFFICE.

FRANZ HUGO THÜMLER, OF CHICAGO, ILLINOIS.

DESIGN FOR A FLASK OR BOTTLE.

SPECIFICATION forming part of Design No. 21,174, dated November 17, 1891.

Application filed October 5, 1891. Serial No. 407,792. Term of patent 7 years.

To all whom it may concern:

Be it known that I, FRANZ HUGO THÜMLER, a citizen of the Empire of Germany, residing at Chicago, in the county of Cook and State of Illinois, have invented a certain Novel Design for a Flask or Bottle; and I do hereby declare the following to be a full, clear, and exact description of the invention, such as will enable others skilled in the art to which it appertains to make and use the same.

This invention relates to a new and original design for flasks or bottles.

In the accompanying drawings, illustrating my invention, Figure 1 is a side elevation of a bottle embodying my design, and Fig. 2 is a vertical sectional view.

The said drawings show a bottle the exterior contour and configuration of which represent a man in the costume of an athlete—namely, the costume of a boxer or wrestler—²⁰ and standing erect upon a base and in front of a post, with arms folded. The effect produced is novel and unique.

I claim as my invention—
The design for a flask or bottle, substantially as shown and described.

In testimony whereof I affix my signature in presence of two witnesses.

FRANZ HUGO THÜMLER.
